CLAIM

We claim the ornamental design for a flashlight, as shown and described.

DESCRIPTION

FIG. 1 is a right-side perspective view of a flashlight showing our new design;

FIG. 2 is a right-side elevational view thereof;

FIG. 3 is a front elevational view thereof;

FIG. 4 is a rear elevational view thereof;

FIG. 5 is a top plan view thereof;

FIG. 6 is a left-side elevational view thereof; and,

FIG. 7 is a bottom plan view thereof.

Throughout the drawings the broken lines depict portions of the flashlight that form no part of the claimed design.
